UNITED STATES PATENT OFFICE.

JAMES W. BODLEY, OF NEW ORLEANS, LOUISIANA.

ROTARY CULTIVATOR.

SPECIFICATION forming part of Letters Patent No. 239,219, dated March 22, 1881.

Application filed January 5, 1880.

To all whom it may concern:

Be it known that I, JAMES W. BODLEY, a resident of New Orleans, in the parish of Orleans and State of Louisiana, have invented 5 certain new and useful Improvements in Rotary Cultivators; and I do hereby declare that the following is a full, clear, and exact description of the invention, which will enable others skilled in the art to which it appertains 10 to make and use the same, reference being had to the accompanying drawings, and to letters of reference marked thereon, which form a part of this specification.

My invention relates to that class of cultivators in which rotary concavo-convex disks are employed in working the soil around sugar-cane, tobacco, and other like plants; and it consists, first, in the improved construction 15 of the devices for adjusting and securing the rotary disks; and, further, in the construction 20 of the draft-bar and its manner of attachment, as fully hereinafter explained.

In the drawings, Figure 1 is a rear view of the cultivator; Fig. 2, a top view; Fig. 3, a 25 front view; Fig. 4, a side view; Fig. 5, a detail sectional view.

Like letters of reference refer to like parts.

A and B are cross-beams, permanently secured to a central beam, F, running lengthwise of the machine. These three beams form 30 the frame of the cultivator, to which the various working parts and their connections are attached. O O are connecting frame-rods. h h are braces. The beam F extends forward 35 and forms the tongue in front, and in the rear it is provided with handles a a, for the operator to guide the machine. The beams B and A are provided with oblong slots b b and c c, near their ends, to receive adjustable clamps 40 connected with the standards and braces which secure the rotary plows in position.

C is a vertical standard, made preferably of wrought-iron or steel, in one continuous piece, screw-threaded at its upper end, and provided 45 with a collar at d, and extending through the slot in the beam B, and adjustably secured to the same by means of a crank-handle nut, e. The lower end of this standard is turned at right angles inwardly, and formed into an 50 axle, f, upon which the rotary disks D D revolve. The end of the axle extending through

the disk is provided with a cross-hole at g, and a cap or washer, h, with corresponding holes through its side, through which passes the end of a brace-rod, I, and is secured thereto by 55 means of a screw-threaded nut. The brace I extends from the end of the axle forward to the beam A, and is secured to an adjustable clamp, i, working in the slot c. This hold-fast i is a screw-threaded bolt, flattened at one 60 end, with a hole in it, and provided with crank-handle-nuts e' e' to hold the same in position.

K is a brace, which is attached to a washer, k, on the axle, on the opposite side of the rotary disk, and extends forward, and is fastened 65 to the hold-fast i by means of a bolt.

L is a side brace, secured to the beam B in the same manner as the standard C, and is attached to the side of the latter by means of a strap, l, around the standard, and bolted to 70 the brace L.

M is a hand-lever, fulcrumed on a spindle, M, which is secured by means of a strap-connection, l, around the standard C, and bolted to the brace L at a point just above the axle. 75

E is a broad-faced traction-wheel, attached to the end of the lever M, not unlike the manner of attaching a wagon-wheel to its axle. When it is desirable to raise the rotary plows from contact with the ground the lever M is 80 secured in an upright position by means of a pin or spring-snap, or other suitable fastening, as shown in Fig. 4, throwing the weight of the machine on the traction-wheels. When it is required to use the plows the lever M is placed 85 in the position shown by the dotted lines in Fig. 4, which nearly balances the wheels and keeps them off the ground while the plows are in use.

G is a draft-rod connected at one end with 90 a washer, k, on the axle at f, and held in a horizontal position at the other end by a chain, H, fastened to the beam A. This chain-connection allows the draft-rod to accommodate itself to the line of draft, and thus avoids the 95 liability of breakage usual where rigid draft-bar connections are used.

n n are whiffletrees. When required to change the inclination of the rotary cutters to the line of draft it is 100 readily done by loosening the nut e on the standard C, which permits the standard and

- axle to turn at any required angle, and by moving the clamp *i* in the slot in the beam *A*, the rotary wheel is held securely in position by means of the braces *I* and *K*. The adjustment of the plows in relation to each other, as to distance apart, is accomplished in the same manner by means of the movable clamp *i* and crank-nuts *e e*, which permits the plows to be moved to and from each other.
- 10 Having described my invention, what I claim, and desire to secure by Letters Patent, is—
1. In combination, the standard *C*, adjustably held in the slotted beam *B*, and capable of rotary motion, the disks *D*, secured upon an axle formed by bending such standards *C* at right angles, the parallel beam *A*, having the slots *c*, and connecting-braces secured to

the axle of the disk and adjustable in such slots *c c*.

2. The combination, with the beams *A* and *B*, provided with slots *c* and *b*, of the standards *C C*, constructed as herein shown, rotary plows *D*, and braces *I K L*, adjustably connected with the beams *A* and *B* by means of crank-nuts *e e* and *e' e'*, substantially as herein shown, and for the purpose set forth.

In testimony that I claim the foregoing as my own I hereunto affix my signature in presence of two witnesses.

JAMES W. BODLEY.
